UNITED STATES PATENT OFFICE.

GEORGE P. STEINBACH, OF BALTIMORE, MARYLAND.

CHILD'S CARRIAGE.

SPECIFICATION forming part of Letters Patent No. 268,140, dated November 28, 1882.

Application filed April 11, 1882. (No model.)

To all whom it may concern:

Be it known that I, GEORGE P. STEINBACH, of Baltimore city, State of Maryland, have invented certain new and useful Improvements 5 in Standards and Canopies for Children's Carriages; and I hereby declare the same to be fully, clearly, and exactly described as follows, reference being had to the accompanying drawings, in which—

10 Figure 1 is a central longitudinal sectional view of a carriage-body embodying my invention. Fig. 2 is a cross-sectional view on the line $x-x$ of Fig. 1. Fig. 3 is an enlarged sectional view of the pivotal connection of the top 15 with the bow, and Fig. 4 is a side elevation of the attachment of the standard to the body.

15 My invention relates to canopies or tops for carriages, and to standards for supporting the same; and it consists in certain features of construction and combinations of parts, as hereinafter described and claimed.

20 In the drawings, A is the carriage-body, of the usual shape and construction, and $a-a$ are side rails bent in the arcs of circles at a' , and 25 firmly attached to the body.

25 B is the canopy, and $b-b$ are the standards. These latter may be attached to the sides of the canopy, if desired; but by preference they are 30 integral with or attached to a bow, b' , which carries a sleeve, E, having a screw-rod, e' , that projects through the canopy. A thumb-screw, e , mounted on the rod e' , serves to clamp the canopy tightly upon the bow. Upon loosening the screw the canopy may be tilted in the direction of the length of the body, or may be 35 slid laterally upon the bow.

35 On the lower ends of the standards are formed arms F, which rest upon the rail, and an arm, b'' , having lug c' , projecting under the 40 rail and carrying a set-screw, f .

40 It will be obvious that upon loosening the screws f the standards may be slid along on the rails a , and may be securely clamped at any desired point by turning up the screws. 45 The standards may furthermore be tilted downward about the curved portions a' of the rail at either end, and may be clamped at any desired angle of inclination.

To the standards b are pivoted, at C, a number 50 of wire bows, on which is mounted a canopy,

py, c , of silk or gingham, adapted to be lowered to shelter the occupant of the carriage in case of rain. It may be lowered to either or both sides, and is normally held up out of the way by straps D, secured to buttons d. In lieu of 55 textile fabric, I may cover the wires with mosquito-netting to exclude flies or insects.

The netting or cover c folds snugly up under the canopy when not in use, as shown, and when netting is used it is of course arranged to lower to both sides at once. Every adjustment of the canopy and netting or cover c is provided for. The canopy may be slid bodily to either end of the rails a , may be tilted as desired, and the part c may be lowered to either 60 side or to both sides at once. Should it be desired to remove the canopy entirely, it is only necessary to loosen the screws f and spring the lower ends of the standards outward until they clear the rails. The arms F constitute 65 a bearing for the standards, extending for a sufficient distance on the rails to give the requisite stability, and they are adapted to fit over the curved ends a' , and secure the standards in an inclined position.

70 I do not confine myself to the precise forms of parts shown, as the same may be modified in many ways without departing from the spirit of my invention; and

I therefore claim—

75 1. In combination with the side rails having curved ends, the standards b and suitable clamping devices for securing them at any point upon the rails, as set forth.

2. In combination with the side rails, the 80 standards b , having arms adapted to rest on the rails, and screws f , whereby the canopy is made readily removable, as set forth.

3. In combination with the standards and canopy, a series of bows hinged to the standards and covered by a textile fabric or netting, forming a supplemental shutter or mosquito-bar, arranged to be lowered upon the body of the carriage and to fold and be secured parallel to the standards, as set forth.

GEO. P. STEINBACH.
